SIGNALING DEVICE

Robert E. Kathriner, Oakland, Calif.

Application January 31, 1938, Serial No. 187,951

1 Claim. (Cl. 116—54)

This invention relates to signaling devices of the type particularly adapted for use on motor vehicles to indicate intended turns.

An object of the present invention is to provide a device of this character in which the signal arm is equipped with a neon tube the energizing current of which is received from the high tension side of the ignition circuit of the motor vehicle so that the use of a second coil is dispensed with.

A further object is to provide a novel switch which may be manually operable simultaneously with movement of the signal arm to indicating position, in non-indicating position of the signal arm the switch being set to pass current from the distributor to a spark plug, and in signaling position the switch being set to pass current from the distributor through the neon lamp and then to the spark plug.

A further object is to provide novel signal apparatus of this type which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification;

Figure 1 is a rear elevation of turn signaling apparatus constructed in accordance with the invention and shown in applied position upon a motor vehicle.

Figure 2 is a longitudinal sectional view of the signal device taken on the line 2—2 of Figure 1.

Figure 3 is a longitudinal sectional view of the signal device taken on the line 3—3 of Figure 2 and showing the switch contacts, also showing the flexible shaft for manually adjusting the signal arm and the switch contacts.

Figure 4 is another longitudinal sectional view of the device taken on the line 4—4 of Figure 2 and showing the stationary stop lugs and movable stop bolt to limit movement of the signal arm in either direction.

Figure 5 is a cross sectional view of the signal device taken on the line 5—5 of Figure 2 and showing the switch contacts in elevation.

Figure 6 is a cross sectional view taken on the

line 6—6 of Figure 1 and showing the neon tube, clamp, and supporting frame of the signal arm.

Figure 7 is a diagrammatic view showing the electrical connections of the signal device with a conventional ignition system.

Referring now to the drawings in which like characters of reference designate similar parts in the various views, the signal arm is shown to comprise a one-piece wire frame 10 shaped to form an arrow, a neon tube 11 of the same shape 10 being housed within the enclosure of the wire frame and being clamped to the latter by a two-piece clamp including side members 12, best shown in Figure 6, shaped to embrace the tube and frame and clamped to both the tube and frame by a plurality of clamp bolts 13.

The signal arm is carried by a switch housing comprising companion shells 14 and 15, best shown in Figure 2, the shell 15 having a tubular bracket arm 16 formed integral therewith and 20 provided with a threaded extension 17 which is passed through an opening in the side 18 of the vehicle. A shoulder 19 is formed on the bracket to engage the outer surface of the side of the vehicle and a clamp nut 20 is threaded on to the threaded extension 17 and engages the inner surface of the vehicle to clamp the signaling device in position.

The shell 14 is rotatably mounted with respect to the shell 15 and to attain this end the shell 14 is provided with an axially disposed hollow shaft 21, best shown in Figure 2. The shaft is internally threaded to receive the threaded end of a shaft 22 which is rotatably mounted in a disc 23 which forms a closure for the shell 15 35 and is removably secured to the shell 15 by screws 24 to permit assembly of the parts. A bushing 25 formed of insulating material is sleeved on the shaft 22 and is fixed to the latter by means of a radially disposed pin 23' adapted to be 40 swung in an arc to rotate the shell 14 through a similar arc and move the signal arm to indicating or non-indicating positions.

As best shown in Figure 4 the shell 14 is provided internally on opposite sides of the axis with integral blocks 26 providing stop shoulders which engage against a stop 27 in the nature of a bolt, carried by the stationary disc 23, as best shown in Figure 2, to limit rocking movement of the signal arm. The longitudinal side portions of 50 the wire frame are secured in openings 28 and are keyed therein by pins 29.

The ends of the neon tube are secured in a block 30 of insulating material confined between the two blocks 26 as best shown in Figure 4. 55

High tension conductor wires 31 and 32 are trained through the hollow rotatable shaft 22 and are terminally directed through suitable openings in the insulating block 30 and connected to 5 the electrodes 33 of the neon tube.

As best shown in Figures 3, 5 and 7 the insulating sleeve is provided with a pair of spaced parallel circumferentially extending switch contacts 34 and 35 and the inner ends of the conductor wires are brought out of the hollow shaft 22 and connected respectively to the contacts 10 34 and 35. A pair of stationary resilient switch contacts 36 and 37 are mounted on a block 38 of insulating material secured to the stationary

15 shell 15 by a screw 39. These spring contacts have wiping engagement with the movable switch contacts 34 and 35 when the signal arm is in indicating position. The insulating sleeve 25 is also provided with a longitudinally extending 20 switch contact 40 which is adapted to bridge the resilient switch contacts 36 and 37 when the switch arm is in non-indicating position.

As best shown in Figure 7 the resilient contact 25 36 is connected by a conductor wire 41 to a spark plug 42 of the vehicle internal combustion engine. The resilient contact 37 is connected by a conductor wire 43 to the distributor 44 of the ignition system, the distributor being connected as is conventional with a conventional high tension 30 ignition coil 45 which need not be described in detail.

When the signal arm is turned to indicating position the current will flow from the distributor through the wire 43, contact 37, contact 35, wire 35 31, neon tube 11, wire 32, contact 34, contact 36, and wire 41 to the spark plug. When the signal arm is turned to non-indicating position current will flow from the distributor 44 to the wire 43, contact 37, bridging contact 40, contact 36, and 40 wire 41 to the spark plug to energize the spark plug.

For actuating the switch arm a flexible shaft 46 is connected to the pin 23, as best shown in Figure 3, and is trained through a cable 47 to a push rod 48, shown best in Figure 1. The push 45 rod may be attached to any convenient part of the vehicle within convenient reach of the driver preferably to the instrument panel 49. The push

rod may be pulled out to swing the signal arm from a perpendicular downward position indicated by broken lines in Figure 1 to a horizontal position indicating a left turn or to an obliquely upward position also indicated by broken lines to indicate a right turn. Simultaneously with the movement of the signal arm to any position indicating the driver's intention the bridging contact will be moved off of the resilient stationary contacts 36 and 37 and the movable contacts 34 and 35 will be brought into contact with the resilient contacts to connect the energizing circuit of the signal arm in series with the spark plug circuit.

To prevent short circuits the stationary shell 15 is provided with a line of insulating material 50 and insulation may be disposed upon other desired parts of the device.

From the above description it is thought that the construction and operation of the invention 20 will be fully understood without further explanation.

What is claimed is:

In a motor vehicle signal device, a rotary shell and a stationary shell disposed edge to edge to 25 form a hollow casing, a bracket arm extending from the stationary shell and adapted to mount the device on a vehicle, a supporting disc at the edge of the stationary shell, a shaft carried by the rotary shell formed to provide a shoulder for 30 abutting one face of the disc, a bushing on the shaft forming a shoulder for abutting the other face of the disc and co-acting with the first named shoulder in preventing separation of the shells, a signal arm extending from the rotary 35 shell, said shaft carried by the rotary shell on the horizontal axis of the said casing and rotatably connected to the supporting disc for disposing the signal arm to swing in a vertical plane, a radially disposed pin connected to said shaft, a cable carried by the bracket arm and connected to said pin for rotating the shaft to actuate the signal arm, a stop pin projecting from the supporting disc into the rotary shell, and shoulders on the rotary shell engageable with the stop pin to limit rotation of the rotary shell in either 40 direction.

ROBERT E. KATHRINER.
